INVENTOR.

William Reynolds

BY

Benj. Webster

ATTORNEY.

UNITED STATES PATENT OFFICE.

WILLIAM REYNOLDS, OF MARYSVILLE, CALIFORNIA.

CONDENSER FOR RADIATORS.

Application filed October 30, 1922. Serial No. 597,807.

To all whom it may concern:

Be it known that I, WILLIAM REYNOLDS, a citizen of the United States, residing at Marysville, county of Yuba, State of California, have invented certain new and useful Improvements in Condensers for Radiators; and I do declare the following to be a full, clear, and exact description of the same, reference being had to the accompanying drawings, and to the characters of reference marked thereon, which form a part of this application.

This invention relates to improvements in means for preventing or lessening the boiling and overflowing of the cooling water from the radiators of automobiles, tractors, and water-cooled motor vehicles generally, this boiling and the consequent overflow and depletion of the water supply being very prevalent in hot weather, and when the engine is doing heavy work, as in climbing a long grade.

The principal object of my invention is to provide a device by means of which, with the forward movement of the vehicle, a continuous flow of relatively cool air will be induced through the overflow or vent pipe of the radiator, acting of course to condense any steam forming on top of the water adjacent said pipe, before it can escape therethrough, and thus preventing the depletion of the supply, besides keeping it cooler than is otherwise the case.

Another object is to provide a device for the purpose which is in the form of an attachment readily applicable to the radiator cap of any motor vehicle, making a hole in said cap being the only thing necessary to be done for the installation of the device.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claim.

In the drawings similar characters of reference indicate corresponding parts in the several views:

Fig. 1 is an elevation of the device itself, substantially full size.

Fig. 2 is a vertical section of the same, 55 showing it as installed in connection with a radiator.

Referring now more particularly to the characters of reference on the drawings, the numeral 1 denotes a radiator having a filler-tube 2, into which projects the open upper end of the usual overflow and vent-pipe 3, the tube being covered as is customary by the removable cap 4.

My cooling attachment comprises a hollow body 5 of suitable size, and preferably of curved and symmetrical outline extending down from the lower end of which is a threaded stem or nipple 6 adapted to be screwed into the cap 4 and then providing communication between the tube 2 and the interior of the body 1.

The body 5 is provided with a plurality of orifices 7 preferably positioned in a common horizontal plane substantially central of the height of the body; the body adjacent said plane however being vertical so that the orifices will be vertically disposed.

This arrangement of the orifices not only gives the best draft with the horizontally directed wind created by the movement of the vehicle, but prevents any dust and other particles from dropping therethrough and into the body and radiator when the vehicle is stationary.

It will therefore be seen that with the forward movement of the vehicle, an upward draft is induced through the vent-pipe 3 and body 5, the lower end of which pipe is of course outside the radiator and open to the atmosphere. This draft or fresh cool air, coming in contact with any steam in or adjacent the tube 2, which is then in effect a steam-dome, causes the condensation of such steam, and its return to the radiator proper 95 as water, before it can escape through the vent pipe.

With the movement of the vehicle, the air would tend to flow straight through the body between the fore and aft holes 7, which 100 would cause any steam to be drawn from the body with the air, instead of allowing it to remain in the body and condense. I therefore hang a flat vertical vane 8 in the body, supported from the top thereof as at 9, this 105 vane being disposed transversely of the vehicle and in the plane of the orifices 7, acting as a baffle or air deflector between the

longitudinally disposed orifices. This vane does not prevent a free circulation of air in the body, but does restrict a too-free flow directly from front to back thereof, which 5 would be detrimental.

The fan however may be omitted, since good results are obtained even without its use.

From the foregoing description it will be 10 readily seen that I have produced such a device as substantially fulfills the objects of the invention as set forth herein.

While this specification sets forth in detail the present and preferred construction 15 of the device, still in practice such deviations from such detail may be resorted to as do not form a departure from the spirit of the invention, as defined by the appended claim.

Having thus described my invention, what 20

I claim as new and useful and desire to secure by Letters Patent is:

A cooling attachment for radiators comprising a hollow ellipsoidal body having a lower orifice arranged for free communication with the interior of the radiator, said body having spaced openings only in the sides thereof, the axial lines of which openings are disposed in the horizontal median plane of the body, and a vertical baffle vane 25 intersecting such median plane of the openings and adapted to be located transversely of the vehicle on which the device is mounted, whereby to prevent a direct current of air flowing through the body longitudinally 30 of the vehicle with the movement of the same.

In testimony whereof I affix my signature.

WILLIAM REYNOLDS.
